Primary Examiner — Sheryl Lane*Assistant Examiner* — Aula Soroush(74) *Attorney, Agent, or Firm* — Garson & Gutierrez, PC(57) **CLAIM**

The ornamental design of a pet enclosure apparatus, as shown and described herein.

DESCRIPTION

FIG. 1 is a perspective view of a pet enclosure apparatus for use as an enclosure, showing our new design;

FIG. 2 is a front side elevation view of the pet enclosure apparatus of FIG. 1, the back side view being identical;

FIG. 3 is a left side elevation view of the pet enclosure apparatus of FIG. 1, the right side view being identical;

FIG. 4 is a top plan view of the pet enclosure apparatus of FIG. 1; and,

FIG. 5 is a bottom plan view of the pet enclosure apparatus of FIG. 1.

The broken lines shown in the drawings illustrate portions of the pet enclosure apparatus that form no part of the claimed design.
